J. D. LANGDON.

VAPORIZING DOME.

APPLICATION FILED NOV. 2, 1916.

1,322,799.

Patented Nov. 25, 1919.

UNITED STATES PATENT OFFICE.

JESSE D. LANGDON, OF WATERVILLE, WASHINGTON.

VAPORIZING-DOME.

1,322,799.

Specification of Letters Patent. Patented Nov. 25, 1919.

Application filed November 2, 1916. Serial No. 129,110.

To all whom it may concern:

Be it known that I, JESSE D. LANGDON, a citizen of the United States, residing at Waterville, in the county of Douglas and 5 State of Washington, have invented certain new and useful Improvements in Vaporizing-Domes; and I do hereby declare the following to be a full, clear, and exact description of the invention, such as will enable 10 others skilled in the art to which it appertains to make and use the same.

This invention relates to a vaporizing dome intended for use in connection with internal combustion engines and designed to 15 be positioned between the carburetor and the intake manifold thereof.

The principal object of the invention is the provision of a device of this character, whereby several of the various products of 20 crude oil may be used as fuel to produce a gas for the engine.

Another object of the invention is the provision of a vaporizer disposed in a vertical position and formed with a circuitous 25 gas passage through it, said vaporizer being provided exteriorly with a water jacket through which is designed to circulate hot water designed to materially assist in the vaporization of the fuel as it passes through 30 the device.

A further object of the invention is to arrange the water jacket of the vaporizing dome in circuit with the water cooling system of the engine and to provide means 35 whereby the water circulation through the vaporizing dome may be controlled at will.

A still further object of the invention is the provision of means whereby the hot water and steam may be admitted from the 40 vaporizing dome water jacket into the circuitous gas passage within the dome for mixture with the hydrocarbon in its passage therethrough.

With these and other objects in view as 45 will appear as the description proceeds, the invention comprises the various novel features of construction, combination and arrangement of parts as will be more fully described hereinafter, and set forth with particularity in the appended claims.

Referring to the drawings,

Figure 1 is a side elevation of my improved vaporizing dome shown attached and operatively connected to an internal combustion engine.

Fig. 2 is a vertical transverse sectional view taken on the line 2—2 of Fig. 3.

Fig. 3 is a vertical transverse sectional view through the vaporizing dome taken on the line 3—3 of Fig. 1.

Fig. 4 is a fragmentary vertical sectional view showing one way my improved vaporizing dome may be detachably connected to the engine intake manifold.

Similar characters of reference are used 65 to denote like parts throughout the accompanying drawings and the following description.

Referring more particularly to the drawings, the reference numeral 1 indicates an 70 inner cylindrical casing which is designed to form an inner hydrocarbon chamber. The upper end of this cylindrical casing is rounded or dome shaped as indicated by the numeral 2, for a purpose which will pres- 75 ently appear.

This inner casing 1 is surrounded by an outer cylindrical casing 3 which is arranged in spaced relation to it and is also provided with a rounded upper or dome shaped end 80 4 arranged in spaced relation to the dome 2 of the inner casing. The lower ends of the inner and outer casings 1 and 3 respectively are connected together, and in this instance to form an integral structure, by a 85 suitably designed bottom 5.

Extending upwardly and centrally through the bottom is a vertically disposed hydrocarbon intake pipe 6 which extends upwardly to a point below and adjacent the 90 dome 2 of the inner casing. The lower end of this intake pipe 6 extends downwardly below the bottom 5 a suitable distance and terminates, if desired, in an angular extension 7 which is provided with an attaching 95 flange 8, whereby the intake pipe may be connected to a suitable carburetor indicated by the numeral 9.

In the preferred form of my invention the vaporizing dome proper is shown formed 100 into and an integral part of the intake manifold 10 of the internal combustion engine. As shown the dome in this instance is disposed intermediate the opposite exhaust ends 11 of the manifold 10 and slightly to 105 one side thereof as clearly shown in Figs. 2 and 3 of the drawings. The intake manifold 10 is attached to the vaporizing dome adjacent the lower end, the bottom 5 being inclined upwardly from the intake pipe 6 110

as indicated by the numeral 12 to the intake manifold, so that any hydrocarbon, water or steam that may exist upon the bottom 5 can be readily and freely sucked into the intake manifold by the suction caused by the operation of the engine.

The space between the inner and outer casings 1 and 3 respectively is designed for the reception of water which is admitted to it from the water outlet manifold 13 through the dome 4 of the outer casing through the medium of a pipe 14. This pipe 14 has one end tapped as at 15 into the water outlet manifold 13, and it is to be understood that this end 15 of the pipe 14 may be tapped into the water outlet manifold in any place found desirable and best suited for the purpose intended. The opposite end of the pipe 14 is suitably attached to a plug 16 that is threadedly connected through the central portion of the dome 4 of the outer casing and is held in position through the medium of a lock nut or other suitable fastening means 17.

The outer casing 3 is provided adjacent its lower end with a water outlet pipe 18 that is tapped through the casing as indicated at 19. Arranged within this outlet pipe 18 is a suitable controlling valve or cock 20 that is provided with an actuating handle or lever 21 whereby the cock may be opened or closed as desired. From the outer casing, the water outlet pipe 18 leads around the motor in this instance and is tapped into the water inlet manifold 22 adjacent its upper end as indicated by the numeral 23.

Tapped into the lower end of the outer casing and at substantially right angles to the outlet pipe 18 is a nipple 24 to which is attached a mixing valve or cock 25 that is provided with an actuating handle or lever 26. A pipe 27 has one end attached to this mixing valve 25 and extends around downwardly beneath the bottom 5 and is tapped through the bottom into the inner hydrocarbon chamber as indicated by the numeral 28.

In the operation of the device, and we will say for instance it is desired to use gasoline for a fuel for the motor, the mixing valve 25 is closed and the valve 20 opened so that a complete circulation of hot water will pass through the vaporizing dome between the inner and outer casing, this water being introduced into the top of the vaporizing dome from the water outlet manifold, and preferably from the hottest point, and is then discharged through the water outlet pipe 18 into the water inlet manifold of the engine. By this arrangement the vaporizing dome will be kept sufficiently heated to produce an efficient vaporizing medium.

When the motor is started the gas is sucked in through the intake pipe 6 and is shot upwardly against the inner heated dome 2 where it is further vaporized and

then passes downwardly between the outside of the intake pipe 6 and the inner surface of the inner casing under the force of gravity to the inlet opening 29 of the intake manifold 10 of the motor, and thence on 70 into the motor.

When it is desired to use heavier hydrocarbon such as kerosene, the cock 20 is opened to permit of a free circulation of hot water through the vaporizing dome. In 75 order to make a highly combustible gas out of kerosene, it is necessary to mix a certain amount of water or steam with it to produce a thorough volatilization of it, and in order to accomplish this, I use the mixing valve 80 25 to control admission of any desired amount of water or steam into the inner hydrocarbon chamber where it will be readily mixed with the fuel in its passage to the motor. In this instance when the motor is 85 started the kerosene gas or vapor is sucked in through the intake pipe 6 and shot against the inner superheated dome 2 where it is further vaporized and then allowed to descend by the force of gravity between the 90 intake pipe 6 and the inner casing 1 and then mixed with the water or steam that is admitted into the inner hydrocarbon chamber through the mixing valve 25, after which it passes out through the opening 29 of the 95 intake manifold 10 into the engine.

It is to be understood, however, that the mixing valve 25 may be used to admit water or steam or both into the inner hydrocarbon mixing chamber of the dome and mixed 100 with any kind of fuel that is being used to an advantage. It is also to be noted that this mixing valve can be actuated to advantage to prevent preignition of the gas when it reaches the engine.

From the foregoing description it will be apparent that through the medium of the hot water jacketed vaporizing dome provided with its circuitous passage vertically disposed, that any hydrocarbon product 105 may be used as a fuel to run the engine in an efficient manner and with a greatly increased amount of power due to the complete vaporization of the hydrocarbon gas in its passage through the vaporizing dome.

While I have shown the vaporizing dome as hereinbefore described formed into and an integral part of the intake manifold of the engine, I desire to have it understood that if found desirable, the vaporizing dome 110 may be made separate and detachably connected in any suitable manner to the intake manifold. In order to better illustrate this, and by reference to Fig. 4, it will be seen that I have provided the vaporizing dome 115 adjacent its lower end with a lateral extension 30 provided with an outlet opening 31 which communicates with the inner hydrocarbon mixing chamber. The outer end of this extension 30 is provided with angular 120

flanges 32 to which is attached the angular flange 33 of the intake manifold lateral extension 34, through the medium of suitable bolts or other suitable fastening means 35.

5 The intake manifold extension 34 is formed integral with the intake manifold 36.

What I claim is:—

1. A vaporizing device embodying an elongated casing having a lateral outlet 10 port near one end, a hydrocarbon inlet pipe extending through said end of the casing past said port to a point near the opposite end of the casing, a water jacket surrounding said casing and having a water inlet 15 and a water outlet, and means for establishing and controlling the flow of water from said jacket into said casing.

2. A vaporizing apparatus comprising a vertical elongated casing having a lateral outlet port near its lower end, a hydrocarbon inlet pipe extending upwardly through the lower end of said casing past said port to a point near the upper end of the casing, a water jacket surrounding said casing and 25 having a hot water inlet at its upper end above the casing and a water outlet near its

lower end, and means for establishing and controlling the flow of water from the lower end of the water jacket into the lower end of the casing.

3. A vaporizing device comprising a vertical elongated casing having a lateral outlet port near its lower end and an inclined portion below said port extending upwardly from the lower end of said casing, 35 a hydrocarbon inlet pipe extending upwardly through the lower end of said casing past said port to a point near the upper end of the casing, a water jacket surrounding said casing and having a hot water inlet and 40 a water outlet near its opposite ends, and means for establishing and controlling the flow of water from said jacket into the lower end of the casing.

In testimony whereof I have signed my 45 name to this specification in the presence of two subscribing witnesses.

JESSE D. LANGDON.
